UNITED STATES PATENT OFFICE

139,173

DESIGN FOR A FLOOR MOP

Clifford L. Cambern, Seattle, Wash.

Application December 13, 1943, Serial No. 111,999

Term of patent 3½ years

(Cl. D9—2)

To all whom it may concern:

Be it known that I, Clifford L. Cambern, a citizen of the United States, residing at Seattle, in the county of King and State of Washington, have invented a new, original, and ornamental Design for Floor Mop, of which the following is a specification, reference being had to the accompanying drawing, forming part hereof.

The dominant features of the design reside in the head portion of the floor mop shown in full lines.

I claim:

The ornamental design for a floor mop, as shown and described.

CLIFFORD L. CAMBERN.
